(57) CLAIM

I claim the ornamental design for the jewelry piece, as shown and described.

DESCRIPTION

FIG. 1 is a front elevational view of a jewelry piece showing my new design;

FIG. 2 is a front perspective view thereof;

FIG. 3 is a right side elevational view thereof;

FIG. 4 is a rear elevational view thereof;

FIG. 5 is a side perspective view shown in an alternate environment;

FIG. 6 is a front elevational view thereof;

FIG. 7 is a front elevational view of a second embodiment of a jewelry piece showing my new design; and,

FIG. 8 is a front perspective view thereof.

The broken lines shown in the drawings illustrate environment and form no part of the claimed design.
